11 Claims. (Cl. 80—43)

This invention relates to metal strip handling apparatus and, more particularly to apparatus arranged to produce steel strip by the rolling process.

In a strip rolling mill consisting of a roughing stand and a finishing stand, it is necessary to continue the production of strip when one of the rolling stands breaks down gradually until it is possible to bring the rest of the stands to a stop. To permit the roughing stands to continue production of strip in such an emergency, a crop-and-cobbler shear is arranged between the roughing train and the finishing train to cut the strip into sheets as it leaves the roughing train. Because of the limitation on conveying distance that can exist between the last stand of the roughing train and the first stand of the finishing train, which distance is limited in order to permit the strip securely to be guided into the finishing train, the lengths into which the strip is cut during cobble-cutting are quite short and the value of such cobble cuts as usable stock is very low. These and other difficulties experienced with the prior art devices have been obviated in a novel manner by the present invention.

It is, therefore, an outstanding object of the invention to provide a metal strip handling apparatus which provides a safe conveying of the forward end of the roll stock from the last stand of a roughing train to the first stand of a finishing train.

Another object of this invention is the provision of a metal strip handling apparatus for strip which provides a method of accumulating sheets of strip when, during an emergency, it is necessary to cobble-cut the strip as it emerges from the roughing train.

A further object of the present invention is the provision of metal strip handling apparatus for strip providing for transmission of the end of the strip from the roughing train to the finishing train, or alternatively, to cut the strip into short lengths in an emergency and stack them for removal.

With these and other objects in view, as will be apparent to those skilled in the art, the invention resides in the combination of parts set forth in the specification and covered by the claims appended hereto.

The character of the invention, however, may be best understood by reference to certain of its structural forms as illustrated by the accompanying drawings in which:

FIG. 1 is a vertical sectional view of a rolling mill apparatus embodying the principles of the present invention.

FIG. 2 is a vertical sectional view of the apparatus taken under a different set of conditions.

FIG. 3 is a transverse sectional view of the invention, FIG. 4 is a plan view of the invention, and

FIG. 5 is a vertical sectional transverse view of an alternative arrangement of the invention.

In general, it is the purpose of this invention to provide a strip rolling mill having at least one crop-and-cobble shear between the roughing and the finish trains with a roller-type conveyor to carry the strip from one train to the other. It is the purpose of the invention to arrange this apparatus so that, in an emergency operation, the strip can be divided into sheets which would be

2

useful for further processing and, nevertheless, so that there will be no difficulty in guiding the strip under normal conditions of operation. A roller element is arranged following the crop-and-cobble shear and a sheet metal receiver is also provided, both of these elements being guided on tracks which extend transversely of the roll pass. The conveyor and the receiver are equal in length and are equipped with a driving device for selecting for location in the roll pass either the roller conveyor for normal operation or the sheet metal receiver for emergency operation. In addition, a roller drive is mounted following the crop-and-cobble shear in which an upper driving roll can be moved upwardly out of working position when the roller conveyor is in place. When the sheet metal receiver is in position, the upper driving roll is moved downwardly into driving position. To simplify the construction arrangement of this device, it is of particular advantage that the roller conveyor and the sheet metal receiver each be mounted on a separate car and that the cars be joined by a flexible connection one beside the other. This makes it possible to move the cars by a common actuating device. The most desirable piling of the sheets which are cut from the strip in emergency operation will be obtained when the sheet metal receiver has a floor which has a slope extending downwardly away from the driving device and is provided with a stationary stop on the end of the receiver away from the driving device. It is contemplated that it will be possible to arrange several sheet metal receivers in side-by-side relationship and to move them during emergency operation successively into alignment with the roll pass.

Following the last roll stand of the finishing train in a strip mill there is arranged a crop-and-cobble shear 1. For the purpose of this application, the expression "crop-and-cobble shear" is used to describe a particular type of shear which is commonly used alternatively to cut off (crop) the forward and rearward ends of a strip or to cut the length of strip into smaller lengths in case of an accident (cobble). It is the function of this shear to rotate continually and cut sheet lengths from a sheet metal strip 2 as it leaves the roughing train at the time of an emergency, such as a breakdown of one of the rolling stands of the following finish train. This cutting takes place until the complete rolling mill can be shut off. Aligned with the crop-and-cobble shear 1 is arranged a roller-type stock-driving device 3 which can be put out of operation under normal operation of the strip mill by moving an upper drive roll 3a upwardly away from the lower drive roll 3b. Following the stock-driving device 3 and in front of the first stand 5 of the finishing train is a foundation hole or pit 4 having tracks 6 arranged transversely of the roll pass. Cars 7 and 8 are movable on these tracks, are flexibly connected one beside the other, and can be driven by a common driving device, for example, by a pressure-medium adjusting motor 9. The car 7 carries a number of conveyor rolls 10 each of which is driven by an individual motor 11 and arranged in a pre-determined distance to form a roller type conveyor 12. The rolls 10 are mounted on parallel axes which are also parallel to the adjustment direction of the cars 7 and 8. On the car 8 is mounted a sheet metal receiver 13 which has a length approximately the same as that of the conveyor 12.

During normal operation of the strip mill, the cars 7 and 8 are moved by the adjusting motor 9 on the track 6 into such a position that the conveyor 12 mounted on the car 7 connects the last roll stand of the roughing train with the first roll stand 5 of the finishing train. The stock or strip 2 coming from the roughing train will be brought immediately into the finishing train, as shown in FIG. 1.

In the event of a breakdown of a rolling stand in the

finishing train, the crop-and-cobble shear 1 will be placed in operation as will the stock-driving device 3. At the same time, the adjusting motor 9 will be energized in such a way that, by moving the cars 7 and 8, the roller conveyor 12 leaves the path of the strip 2 and the sheet metal receiver 13 is positioned behind the stock driving device 3 in the roll pass. The crop-and-cobble shear 1 continues to rotate so that the rolling stock 2 coming from the roughing train will be cut into sheets which will be pushed by the device 3 into the sheet metal receiver 13 and there piled. As is evident in FIG. 2, the sheet metal receiver 13 is equipped with a floor which slopes downwardly away from the device 3 so that the cut sheets fall by gravity and slide against a stationary stop 14. In that way, an accurately adjusted pile 15 of sheet metal sheets is formed in the sheet metal receiver. The floor of the receiver 13 is suitably formed of blocks 16 which have vertical flanges 16a, which are mounted one beside the other in the direction of the roll pass on the car 8, and which serve as a sliding surface for the sheet metal. To make the sliding easy for the first piece of sheet metal, the ends of the blocks which are in the direction of the device 3 are curved downwardly, as is evident in FIG. 2.

During the emergency, after the strip mill has been completely brought to a stop and the damaged roll stand is again ready for operation, the adjusting motor 9 can be energized to bring the roller conveyor 12 into working position by movement of the cars 7 and 8. At that time, the sheet metal receiver 13 moves back into inoperative position. Since the sheet metal receiver 13 is now in an inoperative position away from the roll pass, the sheet pile 15 can be removed by a crane without interfering with the strip mill operation.

Each of the cars 7 and 8 is equipped with four rimless wheels 17 and with four guide pulleys 18, each of which engages a side of one of the tracks 6, as is best evident in FIG. 4.

The modified arrangement shown in FIG. 5 differs from the version shown in FIGS. 1, 2, 3, and 4 only in that a car 28 is provided with several sheet metal receivers 13a and 13b mounted side-by-side, which can be brought into position in alignment with the roll pass when desired. This is accomplished by means of an actuating motor 29 moving the car 28 along tracks 26 on wheels 27. The car 28 is connected along with a car 33 carrying rolls 39 driven by motors 31. Vertically pivoted wheels 32 guide the cars along the track 26 and the adjustment of the cars takes place through a piston rod 48 extending from the motor 29.

A quick-action adjustment is provided for the conveyor 12 and the sheet metal receivers 13. This is made possible by using parallel racks 19 whose teeth face one another and which are joined by a gear 22 pivotally attached to the end of a piston rod 20 which extends from the motor 9, the gear being mounted on a transverse arm 21 to the center of which the piston rod 20 is attached and on the ends of which are mounted the gears 22, one in the vicinity of each track 6. Each of these bevel gears 22 engages a stationary gear rack 23, on the one hand, and a gear rack 24 which is connected to the car 7. When the transverse arm 21 moves with the piston rod 20 the bevel gears 22 roll between the racks 23 and 24; this means that the moving speed of the cars 7 and 8 is twice that of the speed of the piston rod 20.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent is:

1. A metal strip handling apparatus with at least one crop-and-cobble shear arranged between roughing and

finishing trains and with a roller conveyor for carrying the stock from one train to the other

characterized by the fact that a roller element is located after the crop-and-cobble shear coextensively with a sheet metal receiver and guided on common tracks transverse of the roll pass and at the same time selectively movable into the path of the rolling stock to align the roller element with the roll pass during normal operation and to align the sheet metal receiver with the roll pass during emergency operation.

2. A metal strip handling apparatus as recited in claim 1, characterized by the fact that a roller-type stock-driving device is arranged after the crop-and-cobble shear, the device having an upper roll which can be moved upwardly and out of working position when the roller element is aligned with the roll pass and which can be moved downwardly into driving position when the sheet metal receiver is so aligned.

3. A metal strip handling apparatus as recited in claim 1, characterized by the fact that the roller element and the sheet metal receiver are mounted on separate cars which are flexibly connected together.

4. A metal strip handling apparatus as recited in claim 3

characterized by the fact that the cars are movable by a common pressure-actuated device.

5. A metal strip handling apparatus as recited in claim 1

characterized by the fact that the sheet metal receiver has a floor which slopes downwardly and away from the stock-driving device and is equipped with a stationary stop at the end away from the device.

6. A metal strip handling apparatus as recited in claim 1

characterized by the fact that several such sheet metal receivers are arranged for successive movement into the roll pass.

7. Rolling mill apparatus for use with a roughing train and a finishing train having a crop-and-cobble shear following the roughing train, comprising

(a) a pit located between the trains,
(b) tracks mounted at the bottom of the pit and extending transversely of the roll pass,
(c) a conveyor slidably mounted on the tracks and extending parallel to the roll pass,
(d) a stock-receiving frame also slidably mounted on the tracks and extending parallel to the roll pass, and
(e) means for selectively aligning either the conveyor or the frame with the roll pass.

8. Rolling mill apparatus for use in rolling strip with a roughing train and a finishing train having a crop-and-cobble shear following the roughing train, the trains and shear defining a straight roll pass, comprising

(a) a pit located between the shear and the finishing stand,
(b) tracks mounted at the bottom of the pit and extending transversely of the roll pass,
(c) a roller conveyor slidably mounted on the tracks and extending parallel to the roll pass,
(d) an inclined strip-piling frame also slidably mounted on the tracks and extending parallel to the roll pass, and
(e) a linear actuator for selectively aligning either the conveyor or the frame with the roll pass.

9. Rolling mill apparatus for use in rolling strip with a roughing train and a finishing train, comprising

(a) a crop-and-cobble shear following the roughing train, the trains and shear defining a straight roll pass,
(b) means normally located on the roll pass to guide the front end of the strip from the shear to the finish train, and
(c) means movable relative to the roll pass during cobble shearing to receive usable lengths cut from the strip by the shear.

10. Metal strip handling apparatus, comprising
- (a) a finishing train,
  - (b) a crop-and-cobble shear in front of the finishing train,
  - (c) a conveyor normally extending between the shear 5 and the train in line with the roll pass,
  - (d) a stock-receiving frame arranged beside the conveyor, and
  - (e) means operative for moving the conveyor and the frame laterally of the roll pass at the time of cobble 10 shearing so that the frame is in line with the roll pass.
11. Metal strip handling apparatus, comprising
- (a) a finishing train,
  - (b) a crop-and-cobble shear immediately preceding the finishing train,
  - (c) a strip-driving means located in the roll pass following the shear, 15

- (d) a roller conveyor normally extending between the strip-driving means and the finishing train in line with the roll pass,
- (e) an inclined strip-piling frame arranged beside the conveyor, and
- (f) means operative for moving the conveyor and the frame laterally of the roll pass at the time of cobble shearing so that the frame is in line with the roll pass.
